(57) **CLAIM**

The ornamental design for a speaker mounting plate, as shown and described.

DESCRIPTION

FIG. 1 is a top perspective view of a speaker mounting plate according to the present design;

FIG. 2 is a front view of the speaker mounting plate as shown in FIG. 1;

FIG. 3 is a back view of the speaker mounting plate as shown in FIG. 1;

FIG. 4 is a right side view of the speaker mounting plate as shown in FIG. 1;

FIG. 5 is a left side view of the speaker mounting plate as shown in FIG. 1;

FIG. 6 is a top view of the speaker mounting plate as shown in FIG. 1; and,

FIG. 7 is a bottom view of the speaker mounting plate as shown in FIG. 1.

The broken lines shown in FIGS. 1-7 are for purposes of illustrating portions of the speaker mounting plate that form no part of the claimed design.

1 Claim, 5 Drawing Sheets
